(57) **CLAIM**

We claim the ornamental design for a hunting ladder, as shown and described.

DESCRIPTION

FIG. 1 is a front, right side perspective view of a hunting ladder.

FIG. 2 is a front elevational view thereof.

FIG. 3 is a rear elevational view thereof.

FIG. 4 is a right side elevational view thereof, the left side elevational view being identical thereto.

FIG. 5 is a cross-sectional, right side elevational view thereof, taken along the line 5-5 of FIG. 2.

FIG. 6 is a top plan view thereof; and,

FIG. 7 is a bottom plan view thereof.
